UNITED STATES PATENT OFFICE.

ALFRED ERNEST HUDD, OF NEW BRIGHTON, ENGLAND, ASSIGNOR TO AUTOMATIC
TELEPHONE MANUFACTURING COMPANY, LIMITED, OF LIVERPOOL, ENGLAND.

RAILWAY SIGNALING SYSTEM.

Application filed November 6, 1924, Serial No. 748,138, and in Great Britain January 19, 1924.

The present invention relates to improvements in or relating to alternating current track circuits and more particularly concerns the provision of special relay arrangements in place of the usual type of alternating current relays which require a large operating current and can only be operated over comparatively small lengths of track. 5

It has previously been proposed to use in 10 alternating current track circuits vibratory or alternating current to which a relay responds to effect a rectification so that a direct current relay can be operated thereby. In such arrangements difficulties arise in 15 connection with the means for responding to the frequency of alternating current supply. It has been usual to provide a tuned reed 20 for this purpose in order to ensure that the relay will not respond to alternating currents of frequencies different from that of the signaling current.

An important feature of the present invention is that the vibrating reed of the responding relay is not tuned, being in fact 25 substantially aperiodic. Partly in order to render the direct current neutral relay immune to currents of different frequency and partly to enable alterations in the phase of the current flowing over the track to be de- 30 termined, the vibrating relay which responds to the alternating current on the track is ar- ranged to rectify alternating current supplied independently of the track but from the same source as the current which feeds 35 the track. As satisfactory rectification is dependent upon the vibratory member moving in correct phase with the alternating current to be supplied, a further important 40 feature is the provision of phase adjusting means. One form of phase adjustment is to insert a condenser or an inductance in series 45 with the responding relay or in series with the feed circuit or both, a condenser having the additional advantage of protecting the alternating current apparatus, namely, the feed transformer secondary or the responding relay from an accidental connection being established between the live rail and the track rails. The responding relay is pref- 50 erably of the type described in British specification No. 156,353 and such a relay has the additional advantage over relays with tuned reeds that the phase may be adjusted very accurately and very readily. In this con- 55 struction, the polarizing flux is provided by

a U-shaped permanent magnet, each limb of which carries two pole pieces and corresponding coils. The armature is pivoted substantially at its centre of gravity, so as to be practically aperiodic and as may be seen from the figures, in either of its operated positions it extends diagonally between pole pieces of opposite polarity. Moreover the magnet and operating coils are pivoted about the same axis as the armature and adjustment is then readily effected by rotating the coils slightly with respect to the armature, for instance, by means of a threaded screw operating against the action of a restoring spring. Phase variations in alternating current track circuits have always been a considerable source of trouble and have necessitated somewhat expensive mechanism on account of the fact that heavy currents have been used which give rise to much larger variations of phase than the small currents required by the invention and further that the fine phase adjustment could not be affected at the receiving end. With the present invention the lineman has only to place a voltmeter across the terminals of the neutral relay and adjust the responding relay until the voltage recorded is a maximum. 75

In addition to the provision of an aperiodic vibrating relay and special phase adjusting means a further important feature of the present invention in which it differs from prior arrangements is the employment of a polarized relay instead of a neutral relay. The polarized relay is adapted to give different indications depending upon whether the alternating current through the track is in phase with the local alternating current or is 180° out of phase, and this is of considerable value for point detection, three position signaling and other cases where a selective indication is required. 80 85 90 95

The accompanying drawings show by way of example several embodiments of the invention, though naturally additional modifications will readily occur to those versed in the art. 100

Fig. 1 shows an arrangement of a double rail track circuit for non-electrified lines with a standard neutral direct current relay 105 as track relay.

Figure 2 indicates a similar arrangement, in which, however, only one rail is insulated, so that the protective arrangements are different. 110

Figure 3 shows a double rail track circuit with impedance bonds for use with electrified lines, this including a modified arrangement at the receiving end in that double rectification is made use of instead of single rectification as in the preceding cases.

Figure 4 illustrates diagrammatically a similar double rail track circuit with impedance bonds, the relay in this case being shown as a three-position polarized relay.

Referring now to Fig. 1, the track rails of a section are indicated by 1 and 2, this section being isolated from the adjacent sections by the insulators 3 and 4. 5 and 6 represent alternating current power leads carrying a pressure of for instance 230 volts and from these current is fed through the condenser 7 to the track rails 1 and 2. At the other end of the section is the rectifier 8 comprising a sensitive polarized relay which as above mentioned may conveniently be of the type disclosed in British specification No. 156353. When the track is clear, this relay is energized by the alternating current power supplied by way of the condenser 7 to the track rails and operates its armature 9 at a frequency equal to the supply frequency. Each time armature 9 makes contact, a circuit is completed from leads 5 and 6 for the track relay 10 which in this case is shown as an ordinary direct current neutral relay. Since the frequency of vibration of armature 9 is the same as the frequency of the current supplied to track relay 10 from leads 5 and 6, the relay receives pulses of current always in the same direction. It is therefore energized and operates its armatures 11 and 12 so as to close the usual controlling circuits for the signaling system. The non-inductive resistance 13 connected in shunt across the terminals of relay 10 serves to improve its operation and particularly to maintain it continuously operated in response to the pulses of current.

It will be appreciated that the phase relationship of the two currents is of considerable importance and that some adjusting means is therefore desirable to ensure that current shall only be fed to the direct current relay during one half wave. In the case shown general coincidence of phase is secured by the use of the condenser 7 and fine adjustment is effected mechanically at the rectifier 8.

When a train comes on to the rails 1 and 2 of the section under consideration, the rectifier 8 is shorted out in the usual manner, so that armature 9 comes to rest and relay 10 is released. The condenser 7 also serves to limit the current taken from the mains 5 and 6 when the train is on the track which function could of course equally well be performed by a resistance.

The vibrating armature 9 is constructed so as to be sensibly aperiodic, that is to say

it has no natural period of vibrations of its own, and moreover if of the type shown in the specification above referred to, the transit time is small compared with the time of actual contact. This obviates difficulties frequently experienced with tuned vibrating reeds, that under varying conditions of temperature and the like they tend to alter their natural period with the result that sharpness of tuning is impaired and the operation is apt to become unreliable. In the present case this clearly cannot happen and the certainty of operation is independent of external physical conditions. Moreover, while tuned reeds will not normally respond to currents of other frequencies, they are apt to be thrown into forced vibrations by such currents if large and again, the ordinary sensitiveness may be impaired. According to the present invention, the rectifier could of course respond equally well to stray currents of frequency different from that of the power source, but as the feeding current for the relay 10 remains unaltered in frequency, rectification cannot take place. Under these circumstances the relay 10 is prevented from energizing intermittently on occasional accidental phase correspondence by its inertia and by the effect of the non-inductive resistance 13.

Fig. 2 shows an arrangement for electrified lines with a single rail track circuit, that is to say rail 15 is continuous while rail 16 is split up by insulators such as 17 and 18. The feed is now from power mains 20 through transformer 19, the secondary circuit including condenser 21. The rectifier 22 is in this case connected through condenser 23 and the impedance 24 which serve to protect the rectifier in case of contact between the traction live rail and the track rail 16 used for signaling purposes. Condenser 21 serves to protect the transformer from a similar contingency while also fulfilling current limiting and phase adjusting functions. The feeding current for the track relay 27 is also in this case supplied through a transformer 26, the arrangement of the vibrating contact 25 and the non-inductive resistance 28 being as before. Armatures 29 and 30 of the track relay will again control circuits as required in the same manner as with ordinary track circuiting. The arrangement shown in Fig. 2 it will be noted provided complete isolation from the direct current traction circuits.

In Fig. 3 is shown a modified arrangement employing double rectification at the receiving end, the arrangements being otherwise similar to Figs. 1 or 2. The track rails are represented by 31 and 32 and 33 is the rectifier controlling a vibrating contact 36. In this instance, however, armature 36 makes contact in each of its extreme positions and the track relay comprises two

coils 37 and 38, shunted respectively by non-inductive resistances 39 and 40. Current is supplied at 34 to the primary of the transformer 35 and the secondary is connected 5 to the vibrating contact 36 and to the junction of windings 37 and 38. Hence when 10 the rectifier receives current over the track (supplied as before from the same source as 34) pulses of current are fed alternately to 10 coils 37 and 38. Clearly a pulse is now obtained for each half of the wave and additional security is obtained against the tendency of the track relay to release between the pulses.

15 In Fig. 4 is shown an arrangement for electrified lines with a double rail track circuit so that impedance bands 43 and 44 are necessary to isolate the sections for signaling purposes while giving an uninterrupted return 20 for the traction current. Current is supplied from mains 45 to the transformer 46, from the secondary of which it is fed to the rails 41 and 42 by way of the condenser 47. The arrangements at the receiving end 25 include the use of a three-position track relay, this relay taking up in addition to its neutral position a different operated position according as the controlling currents are in phase or 180° out of phase. The rectifier 30 48 is similar to that shown in Figs. 1, 2 and 3 and controls a vibrating contact 49. The three-position relay is preferably constructed with a closed annular core 53 on the two halves of which are located the coils 35 51 and 52, wound so as to give consequent poles at the junctions. The ring and coils are assumed to be located in a vertical plane. Pivoted axially at the centre of the coil on a pivot 55 is a permanent magnet 54, preferably 40 of cobalt steel, arranged to occupy a vertical position when no current is fed to the relay. This magnet controls armature 56 so as to close either contact 57 or 58 when the magnet swings to one side or the other. Current is supplied from the power 45 mains 45 through the transformer 50 in the same manner as in Figs. 2 and 3, and the relay is again shunted by a non-inductive resistance 59.

50 In operation, current is transmitted over the track in the usual manner and operates the armature 49 of the rectifier 48 at the supply frequency. Each time armature 49 engages its left hand contact a circuit is completed 55 from the secondary of the transformer 50 for the coils 51 and 52 in series. Consequent poles are therefore produced, for instance as shown, and the magnet 54 is rotated in a clockwise direction so as to cause armature 56 to engage with contact 57.

56 If however a reversing switch is provided in the leads supplying the transformer 46 or the transformer 50, for instance as shown at 60 and this switch is operated, the phase 65 relationship of the two currents controlling

the relay is altered by 180°. Consequently the pulses of current fed to the coils 51 and 52 are now in the opposite direction, so that poles are developed in the core 53 opposite to those shown and magnet 54 thus 70 swings in the other direction to close the contact 58.

75 Thus by means of this arrangement it is possible to use a polarized relay and hence obtain three operated positions while retaining the special advantages incidental to the use of alternating current in this connection.

What I claim is:—

1. A railway signaling system comprising 80 in combination an insulated section of track, a source of alternating current connected to one end of said track, a polarized relay connected to the other end of said track, a substantially aperiodic vibrating contact member controlled by said relay, a direct current relay, means for rendering said direct current relay sluggish and means for connecting said source of alternating current, said vibrating contact member and said direct current relay in series so that when said contact member vibrates at the frequency of said alternating current source, uni-directional 85 pulses of current are fed to said direct current relay. 90

2. A railway signaling system comprising 95 in combination an insulated section of track, a source of alternating current connected to one end of said track, a condenser in circuit with said alternating current source for determining the phase thereof, a polarized relay connected to the other end of said track, a vibrating contact member controlled by said relay, a direct current 100 relay, means for rendering said relay sluggish and means for connecting said source of alternating current, said vibrating contact member, and said direct current relay in series so that when said contact member vibrates at the frequency of said source and has the correct phase relation, uni-directional 105 pulses of current are fed to said direct current relay. 110

3. A railway signaling system comprising 115 in combination an insulated section of track, a source of alternating current connected to one end of said track, a polarized relay connected to the other end of said track, a vibrating contact member controlled by said polarized relay, a second polarized relay, means for rendering said second relay sluggish and means for connecting said source of alternating current, said vibrating contact member and said second polarized relay in series, so that 120 when said contact member vibrates at the frequency of said alternating current source uni-directional pulses of current are fed to said second polarized relay which is thereby 125 operated in one direction or the other. 130

according as the vibrations of said contact member are in phase or 180° out of phase with said alternating current source.

4. A railway signaling system comprising in combination an insulated section of track, a source of alternating current connected to one end of said track, a condenser in circuit with said alternating current source for determining the phase thereof, a polarized relay connected to the other end of said track, a substantially aperiodic vibrating contact member controlled by said polarized relay, a second polarized relay, a resistance connected across the terminals of said second relay and means for connecting said source of alternating current, said vibrating contact member and said second polarized relay in series so that when said contact member vibrates at the frequency of said source of alternating current, uni-directional pulses of current are fed to said second polarized relay which is operated in one direction or the other according as the vibrations of said contact member are in phase or 180° out of phase with said alternating current source.

5. A railway signaling system comprising in combination an insulated section of track, a source of alternating current connected to one end of said track, a condenser in circuit with said alternating current source for determining the phase thereof, a polarized relay connected to the other end of said track, a substantially aperiodic vibrating member controlled by said relay, a direct current relay, means for rendering said direct current relay sluggish, means for connecting said source of alternating current, said vibrating member and said direct current relay in series, and adjusting means associated with said polarized relay for varying the relationship between the phase of the current received by said relay and the phase of the vibrations of said contact member.

6. A railway signaling system comprising in combination an insulated section of track, a source of alternating current connected to one end of the said track, a condenser in circuit with said alternating current source for determining the phase thereof, a polarized relay connected to the other end of said track, a substantially aperiodic vibrating member controlled by said relay, means for adjusting the relative positions of said vibrating member and the pole-pieces of said polarized relay, a direct current relay, a resistance connected across the terminals of said direct current relay, and means for connecting said source of alternating current, said vibrating member and said direct current relay in series.

7. A railway signaling system comprising in combination an insulated section of track, a source of alternating current connected to

one end of said track, a polarized relay connected to the other end of said track, a vibrating contact member controlled by said polarized relay, a second polarized relay, means for rendering said direct current relay sluggish and connecting means independent of said track for connecting said source of alternating current, said contact member and said second polarized relay in series, so that when said contact member vibrates at the frequency of said source of alternating current, uni-directional pulses of current are fed to said second polarized relay which is operated in one direction or the other according as the vibrations of said contact member are in phase or 180° out of phase with said alternating current source.

8. A railway signaling system comprising in combination an insulated section of track, a source of alternating current connected to one end of said track, a polarized relay connected to the other end of said track, a vibrating contact member controlled by said polarized relay, a second polarized relay comprising an annular core, energizing windings on said core arranged so as to produce consequent poles at opposite ends of a diameter, a permanent magnet pivoted on the axis of said core, contacts closed by said magnet when operated to either of its extreme positions, a resistance connected across the terminals of said second polarized relay and means for connecting said source of alternating current, said vibrating member and said second polarized relay in series.

9. A railway signaling system comprising in combination an insulated section of track, a source of alternating current connected to one end of said track, a polarized relay connected to the other end of said track, a vibrating contact member controlled by said polarized relay, a second polarized relay, means for rendering said second relay sluggish, means for connecting said source of alternating current, said vibrating contact member and said second polarized relay in series and means for altering by 180° the relationship between the phase of the current received by said second polarized relay and the phase of the vibrations of said contact member.

10. A railway signaling system comprising in combination a pair of track rails, insulators dividing said track rails into sections, a source of alternating current connected to one end of one of said sections, a condenser in circuit with said source of alternating current for determining the phase relationship thereof, a polarized relay connected to the other end of said section, a substantially aperiodic vibrating contact member controlled by said polarized relay, a direct current relay, a resistance connected across the terminals of said direct current relay, means for connecting said source of alternating current, said vibrating contact member and said direct current relay in series.

alternating current, said vibrating contact member and said direct current relay in series and contacts controlled by said direct current relay for opening or closing points

5 in the signaling circuits.

11. A railway signaling system comprising in combination a pair of track rails, insulators dividing said rails into sections, impedance bonds bridging said insulators, a

10 source of alternating current, a transformer having its primary fed from said source, a condenser, means for connecting the secondary of said transformer across said track

15 rails at one end of one of said sections in a circuit including said condenser, a polarized relay connected across said track rails at

the other end of said section, a substantially aperiodic vibrating member controlled by said polarized relay, a second polarized relay, a resistance connected across the terminals of said second polarized relay, a second transformer having its primary also fed from said source, means for connecting the secondary of said second transformer, said vibrating contact member and said second polarized relay in series and contact members connected in the signaling circuits and closed by said second polarized relay in its operated positions.

Signed by me at Cheshire, England this 30
17th day of October 1924.

ALFRED ERNEST HUDD.
